WESTERN ELECTRIC COMPANY, INCORPORATED, A CORPORATION OF NEW YORK.

TELEPHONE-EXCHANGE SYSTEM.

1,189,458.

Specification of Letters Patent. Patented July 4, 1916.

Application filed May 10, 1915. Serial No. 27,037.

To all whom it may concern:

Be it known that I, ALBEN EMANUEL LUNDELL, citizen of the United States, residing at New York, in the county of Bronx and State of New York, have invented certain new and useful Improvements in Telephone-Exchange Systems, of which the following is a full, clear, concise, and exact description.

This invention relates to telephone exchange systems employing machine switching. Its object is to provide a simplified connector circuit.

In connector circuits wherein the stepping magnets are operated under control of a distant sender, a slow relay is employed whose function is to operate to effect the change-over operations at the end of each of the series of interruptions of the line circuit caused by the sender in transmitting the tens and units digits of the wanted line.

A feature of the invention consists in a circuit arrangement wherein the slow relay above referred to is also used as the called supervisory relay after having co-operated in the setting of the connector on the wanted line terminals, and due to its being a slow relay, it provides the delayed disconnect feature, that is, it prevents the connection from being destroyed by an accidental momentary opening and closing of the line circuit by the called party.

Another feature of the invention consists in providing this relay with a second marginal winding adapted to be included in circuit with the ringing generator and the called line, and to operate upon the response of the called party and open the ringing circuit, the first mentioned winding of the relay at this time being connected to one of the talking conductors of the connecting circuit to give a signal or ringing tone to the calling party to inform him that the called party is being signaled.

The invention will be more readily understood when described with reference to the accompanying drawing. For simplicity the connector circuit only is shown, it being understood that a connection would ordinarily lead from the calling substation A through one or more finders and group selectors, and finally through the connector shown, to the called substation B. When the calling line has been extended through to the connector, therefore, the relay 10

thereat is energized over the following circuit: free pole of the battery, left winding of relay 10, conductor 1, terminal 2, selector brush 3, line conductor 4, telephone set of the calling substation A, sender S thereat, line conductor 5, selector brush 6, terminal 7, conductors 8, 9, right winding of relay 10 to ground. This relay at its armature and front contact closes a circuit for slow-acting relay 11. Relay 11 then, at its left hand armature and front contact, extends the back contact of the stepping relay 10 to the primary stepping magnet 15. The calling subscriber now operates his dial S to send a series of impulses corresponding to the tens digit of the wanted number. Each time the armature of the relay 10 closes its back contact, the following circuit is closed for the primary magnet 15 which steps the connector brushes 40, 35, 62 into operative relation to the group of terminals containing the wanted line: free pole of battery, magnet 15, conductor 18, side switch arm 19 and its first contact, conductor 20, left-hand armature and front contact of slow relay 11, conductor 21, armature and back contact of stepping relay 10 to ground. The relay 11 is slow-acting and is maintained energized during the breaks in the line circuit in sending this series of impulses. Upon the first closure of the back contact of the stepping relay 10, due to the first interruption of the line circuit in sending this series of impulses, the slow relay 12 was energized over the following circuit: free pole of battery, left winding of relay 12, conductor 22, side switch arm 23 and its first contact, conductor 24, left-hand non-inductive winding of slow relay 11, left-hand armature and front contact thereof, conductor 21, armature and back contact of stepping relay 10 to ground. Therefore, when the stepping relay 10 is maintained energized at the end of the series of interruptions corresponding to the tens digit of the wanted number this relay 12 is deenergized. When relay 12 became energized, in attracting its right armature into engagement with contact spring 25, a circuit was closed for the magnet 13 which is the side or steering switch escapement magnet. This magnet operates in the well-known manner to release the side switch upon its deenergization. Therefore, when the slow relay 12 is deenergized at the end of the series

of interruptions of the line circuit corresponding to the tens digit of the wanted line the magnet 13 releases the side switch into position 2. In this position, side switch arm 19 transfers the back contact of the stepping relay 10 into connection with the secondary magnet 16. The subscriber now operates his sender S which causes the line circuit to be interrupted a number of times, corresponding to the units digit of the wanted line. Upon the first interruption of the line circuit, the armature of the stepping relay 10, in closing its back contact, again energizes the slow relay 12 as before but now over side switch arm 23 and its second contact. Side switch escapement magnet 13 is consequently energized over the following circuit: free pole of battery, magnet 13, conductor 27, spring 25, right armature of slow relay 12, side switch arm 26 and its second contact to ground. Each time the stepping relay 10 is deenergized, it sends an impulse to the secondary vertical magnet 16 over the following circuit: free pole of battery, magnet 16, conductor 74, side switch arm 19 and its second contact, conductor 20, left armature and front contact of slow relay 11, conductor 21, armature, and back contact of stepping relay 10 to ground. The magnet 16 consequently steps the connector into connection with the wanted line. The slow relay 12 is deenergized as before at the end of the series of circuit interruptions, due to the maintained energization of the stepping relay 10, whereupon the escapement magnet 13 releases the side switch into position 3, in which ringing current is applied to the selected line, if idle. Side switch arm 58 in moving into position 3 places a ground upon multiple test terminals 59 in the connectors to render the line busy, this ground being maintained in position 4.

In position 3, the side switch escapement magnet 13 is energized by the arm 26 moving into this position 3 over the following circuit: free pole of the battery, magnet 13, conductor 27, spring 25, conductors 75, 28 and 29, side switch arm 26, and its third contact to ground. The magnet 13, at its armature and front contact, connects the pulsating current generator 30 to the called line to signal the wanted subscriber. This circuit is as follows: free pole of generator 30, lamp 31, armature and front contact of magnet 13, right winding of slow-relay 12, conductor 32, arm 33 and its third contact, conductor 34, connector brush 35, contact 36, conductor 37, bell 43 and condenser 70, conductor 38, contact 39, brush 40, conductor 41, arm 42 and its third contact to ground. This current operates the bell 43 at the called substation B, but is not of sufficient strength to energize the relay 12. In this position arm 23 connects the left-hand winding of relay 12 to conductor 48 which

is connected to talking conductor 46. Thus, the calling subscriber is given a characteristic signal, indicating to him that the wanted party is being rung, since the ringing current passing through the right-hand winding of relay 12 will induce currents in the left-hand winding of said relay.

When the called party removes his receiver and thus shunts bell 43 and condenser 70, the right-hand winding of relay 12 receives sufficient current to cause it to attract its armatures. The engagement of the right-hand armature with contact spring 25 opens the circuit previously traced for the side switch escapement magnet 13 to ground by way of the side switch arm 26, whereupon the side switch is released into position 4, in which position arms 23 and 26 close the following circuit to supply talking current to the called subscriber: free pole of the battery, left-hand winding of relay 12, conductor 22, arm 23 and its fourth contact, conductor 44, right winding of impedance coil 45, conductor 46, arm 33 and its fourth contact, conductor 34, connector brush 35, contact 36, out over the called line and through the telephonic apparatus thereat by way of the conductors 37, 38, contact 39, connector brush 40, conductor 41, arm 42 and its fourth contact, left-hand winding of impedance coil 45, conductor 47, side switch arm 26 and its fourth contact to ground. While the left winding of the relay 12 is included with the right winding of the retardation coil 45 in one side of the talking circuit, whereas the other side of the circuit contains only the left winding of the retardation coil, this relay and retardation coil are so wound as not to unbalance the talking circuit.

If the called party should depress his receiver hook momentarily after having responded, the connection would not be destroyed since the relay 12 is slow-acting and its left armature would not close its back contact which controls the circuit of release magnet 14. When, however, at the termination of the conversation, the called party replaces his receiver upon its switchhook, and assuming the calling party has not yet replaced his receiver, the relay 12, after an interval allows its armatures to fall back to release the connector. The release circuit is as follows: free pole of the battery, release magnet 14, conductors 49, 50, 51, left-hand armature and back contact of slow relay 12, conductor 52, arm 53 and its fourth contact to ground. Upon the energization of release magnet 14, it closes a locking circuit for itself as follows: free pole of the battery, release magnet 14, conductor 49, contacts 54 and 55, conductor 56, resistance 71, armature and front contact of relay 11 to ground. The release magnet in energizing, restores the connector and side switch in the

well-known manner, and applies tone from a busy back apparatus 64 to indicate to a calling party that the called party has hung up his receiver. When the calling party hangs up his receiver the relay 10 is deenergized, and its armature in retracting releases relay 11, which at its left armature and back contact closes ground to conductor 69 leading to the preceding switches to release the same, this circuit leading by way of spring 65 of the connector now closed to its left or normal contact. This ground renders the connector selectable by another testing selector. The retraction of the right armature of relay 11 deenergizes magnet 14. In case the line selected had been busy as a called line, ground would have been present on test terminal 59, due to the side switch arm 58 of the connector connected therewith being in position 3 or 4. In case the selected line had been busy as a calling line, ground would have been present on the test terminal 59, through a contact (not shown) of the finder or equivalent switch. In this event, when the circuit of the slow relay 12 is broken by the maintained attraction of the armature of relay 10, after the series of interruptions of the line circuit corresponding to the units digit of the wanted number has been sent, the following circuit is closed to the connector release magnet 14: free pole of the battery, release magnet 14, conductors 49, 50, 51, left armature and back contact of slow relay 12, conductor 52, side switch arm 53 and its second contact, conductors 28, 60, side switch arm 58 and its second contact, test conductor 61, test brush 62 to grounded test contact 59. The release magnet immediately restores the connector and side switch to normal, and locks itself up in a circuit controlled at the right armature and front contact of slow relay 11 over the circuit previously traced. At its lower armature release magnet 14 connects the busy back mechanism 64 to conductor 48 connected to conductor 46 to indicate to the calling party that the wanted line is busy. When the calling party restores his receiver, relay 10 becomes deenergized and releases relay 11. The right armature of relay 11 in falling back opens the circuit of release magnet 14, which disconnects the busy back mechanism.

In case the calling party abandons the call after having partially set the connector or before the called party answers, the connector is released by the closure of the following circuit: free pole of battery, release magnet 14, conductors 49, 50, 67, side switch arm 76 and its first, second or third contact, conductor 68, spring 65 and its right or off-normal contact, conductor 69, left armature and back contact of relay 11, conductor 21, right armature and back contact of relay 10 to ground. The magnet 14 thereupon re-

leases the connector, and locks up over the following circuit: free pole of battery, magnet 14, conductor 49, springs 54, 55, conductor 56, off-normal contact 57 to ground, and is deenergized by the opening of this off-normal contact when the connector reaches its normal position.

What is claimed is:

1. In a telephone exchange system, the combination with telephone lines, means for interconnecting the same including connectors, a steering switch and a release circuit for each connector, a slow relay adapted to control the same, and means actuated upon the response of the called party for including said slow relay in circuit with the called line.

2. In a telephone exchange system where in a slow-acting relay is employed at the connector to control a steering switch to effect the changeover operation at the end of each series of line circuit interruptions caused by the sender, the combination with the connector, the slow relay and the steering switch, said steering switch being adapted when operated upon the termination of the last series of circuit interruptions to include said slow relay in circuit with the called line, said relay being adapted to respond when the called party answers, and a release circuit for said connector controlled at a back contact of said slow relay.

3. In a telephone exchange system, the combination with a calling and a called line, telephonic apparatus and signal receiving devices therein, means for interconnecting said lines including connector switches, a source of ringing current, of a double wound relay, and means for applying current from said source to the called line over a circuit including one winding of said relay and the signal receiving device in said line and for connecting the other winding in circuit with the calling line and the telephonic apparatus therein to give a ringing signal to the calling party, said relay being adapted to operate upon the response of the called party to open the ringing circuit.

4. In a telephone exchange system, the combination with telephone lines, means for interconnecting the same including connector switches, a ringing generator, a steering switch for each of said connectors, a stepping relay, a circuit therefor, a sender in said circuit for intermittently operating said stepping relay, a double wound slow-acting relay controlling said steering switch, one of the windings of said relay being connected to the back contact of said stepping relay by said steering switch, whereby upon the cessation of the last series of circuit interruptions said slow relay causes said steering switch to advance to the next position, in which said switch transfers said winding into circuit with the calling line and the

other winding in circuit with said ringing generator and the called line, means actuated upon the response of the called party for operating said slow relay to advance said steering switch to the next position, a retardation coil, said switch in said position transferring said first mentioned winding

into circuit with said coil and the called line, and a release circuit for said connector controlled at a back contact of said slow 10 relay.

In witness whereof, I hereunto subscribe my name this 8th day of May A. D., 1915.

ALBEN E. LUNDELL.
